UNITED STATES PATENT OFFICE.

WILLIAM R. HODGES, OF EUPORA, MISSISSIPPI.

ADJUSTABLE-SHACKLE DOLLY.

Application filed May 21, 1925. Serial No. 31,888.

This invention relates to improvements in adjustable shackle dollies for the holding of rivets while the same are being formed.

The primary object of the invention is the provision of an improved mechanical device particularly well adapted for the holding of rivets in place while the same are being driven and formed, without the attendant manual exertion necessary with conventional dollies.

10 A further object of the invention is the provision of a rivet holder or jam dolly, embodying a relatively simple and adjustable arrangement of parts, having a powerful leverage action by means of which very little manual exertion is necessary to effectively hold the rivets in place while the same are being driven.

Further objects and advantages of this invention will be apparent during the course 20 of the following detailed description.

In the accompanying drawing, forming a part of this specification, and wherein similar reference characters designate corresponding parts throughout the several views.

25 Figure 1 is a side elevation, partly in section, showing the manner in which the improved device is used for holding an upper rivet while the same is being driven or formed.

Figure 2 is a view showing a further use 30 of the tool, for the forming of a lower rivet, using the prior placed upper rivet as a centering means for the tool.

Figures 3 and 4 are cross sectional views taken substantially on their respective lines 35 in Figure 1 of the drawing.

In the drawing, wherein for the purpose of illustration is shown only the preferred embodiment of this invention, the letter A may generally designate the improved tool, which 40 is adapted to be used in connection with the placing of rivets for the connection of structural steel forms, such as channels B, upon any other structural framing C. The improved tool is preferably adapted to be used 45 in connection with riveting of steel bridge construction, but may be practicably adapted for use in connection with boilers, tanks, and other approved forms of work using structural steel framing.

50 As used in bridge work, the tool finds its most practical adaptation in connection with the channels B, which as is well known includes the upper and lower flange portions 10 and 11, provided with openings 13 and 14 55 for receiving upper and lower rows of rivets 15 and 16, for connecting the channels B to

the framing C. This is merely by way of example, in order to more clearly illustrate the use of the tool A.

Referring to the details of the tool A, the 60 same is relatively simple, consisting of a frame 20; and pivot bars or shanks 21 and 22 adjustably and pivotally connected with the frame 20.

The frame 20 is of any approved metal, preferably steel, and comprises the loop shaped shank supporting end 25, having longitudinally extending sides 27 and 28, preferably in parallel relation, connected forwardly by an end 29 integral therewith, and rearwardly 65 tapering at 30 and 31, into integral connection with a preferably straight handle 33, which is rounded at its rearhand engaging end 35, as is illustrated in the drawing. In cross section, the sides and end of the elongated loop 25 are rectangular, and the loop provides the elongated opening 35 therein, for adjustably receiving the rivet bars or shanks 21 and 22. The sides 27 and 28 of the frame loop 25 are preferably provided with a 70 pair of aligning openings 37 and 38 transversely therethrough, adjacent the end 29, and a second pair of transversely aligning openings 39 and 40 closer to the handle 33, and which pairs of aligning openings are 75 respectively adapted to receive pivot pins or members 41 and 42, by means of which to pivotally connect the shanks 21 and 22 to the frame 20. The pins 41 and 42 each include 80 heads 44 adapted for abutment at one of the sides of the loop 25, and at their opposite ends are transversely apertured for receiving cotter pins 45 whereby to support the said pins in parallel relation extending across the opening 35 of the loop 25, for the pivotal reception 85 of the shanks 21 and 22, as will be apparent.

The shanks 21 and 22 are somewhat identical, each of the same being preferably square in cross section, and the same being rugged, and at their outer ends having rivet 90 head cup recesses 50 and 51 respectively. The shank 21 is preferably provided with a series of longitudinally extending recesses 54, through which the pin 42 may be selectively placed to connect the shorter shank 21 95 to the frame 20, with its cup recess 50 at a desired spaced relation from the frame 20. In analogous manner the shank 22 is preferably provided with a series of transverse openings 55, adapted to receive the pin 41 for 100 connecting the shank 22 to the frame loop 25, to place its cup recess 51 in a desired 105

spaced relation to the loop 25, and at the opposite side of the plane of the loop 25 from the shank 21, as is illustrated in the drawing. The placing of the pins 41 and 42 is such that the shanks 21 and 22, may be moved into abutment at their facing side surfaces 58 and 59, as is illustrated in the drawing; the said shanks at their faces 58 and 59 being slightly spaced at their sides when at exactly right angles to the plane of the loop 25, to permit limited play of the handle 33, so that when the latter is moved into oblique relation to the axes of said shanks, the latter will be drawn into abutting adjacement at their surfaces 58 and 59 for locking the same in a particular linear arrangement. If desired, at the free end adjacent the cup recesses 50 and 51 the shanks may be tapered, as at 60, to facilitate access of the tool in close quarters.

An important feature of the invention is the provision of a work engaging pin 65, which may suitably be termed a stinger, and which is adapted to be placed in a socket 67 suitably provided axially inwardly of the recessed end of the shank 21; said pin 65 having a diametrical passageway 68 therethrough adapted for alignment with a way 69 extending through the shank 21, to receive a cotter pin 70, or the like, by means of which the stinger or pin 65 may be held in place, with its pointed end 72 extending beyond the edge of the shank 21. It is to be noted that the pin 65 axially extends through the rivet head receiving cup or recess 50 of the shank 21.

Referring more particularly to the use of the tool, the shanks 21 and 22 are of course adjustable with respect to the frame loop 25, so that their rivet engaging ends may be spaced at a particular distance according to the width of a channel or other structural piece being worked upon. In riveting above and below from the flanges of channels, for the fastening of an upper rivet 15, the stinger or pin 65 will rest upon the channel flange below, or any other suitable framing, and the rivet 15 is placed in the opening 13, and the lever or handle 33 moves with respect to the

shanks so that the head 75 of the rivet 15 is received in the recess 51 of the shank 22, and upon movement of the handle 33 the shanks 21 and 22 will be locked together and the rivet forced into place and held in an absolutely fixed relation so that the operator may drive the head at the opposite end. After the upper rivet has been placed, the pin or stinger 65 will be removed, and the adjustable dolly turned to an angle of 180°, so that the shank 21 may be uppermost, and the rivet head recess 50 of the shank 21 is then centered on the head 75 of the upper rivet 15 and the lower rivet 16 may be placed, and the tool A moved so that the shank 22 engages the head 80 of the lower rivet 16, in the relation shown in Figure 2 of the drawing, and an operator may drive the head of the rivet 16 on the outer side of the channel.

With the use of the improved tool A there is no waste of materials by ruining of rivets, and riveting work may be expedited. The improved tool may be operated by an ordinary person since very little manual exertion is necessary to use the same.

Various changes in the shape, size, and arrangement of parts may be made to the form of invention herein shown and described, without departing from the spirit of the same or the scope of the claim.

I claim:

In a shackle dolly of the class described the combination of a handle frame, a pair of shanks, means pivotally connecting the shanks to the frame, each of the shanks at the free end thereof having a rivet head receiving socket therein, one of said shanks axially therewith and inwardly in communicating relation with the rivet head receiving socket having a reduced socket, a work engaging pin having a pointed end, the work engaging pin being adapted to extend into the last mentioned reduced socket, and means for connecting the pin in said reduced socket in detachable relation with the pointed end extending beyond the free end of the respective shank.

WILLIAM R. HODGES.
